UNITED STATES PATENT OFFICE.

WALDO E. ROSEBUSH, OF APPLETON, WISCONSIN.

FIREARM.

1,291,688.

Specification of Letters Patent. Patented Jan. 14, 1919.

Application filed August 30, 1918. Serial No. 117,680.

To all whom it may concern:

Be it known that I, WALDO E. ROSEBUSH, a citizen of the United States, and a resident of Appleton, in the county of Outagamie and State of Wisconsin, have invented a new and Improved Firearm, of which the following is a full, clear, and exact description.

The invention relates to recoil operated breech loading automatic hand firearms, and its object is to provide a new and improved firearm arranged to permit intermittent or automatic firing. Another object is to allow ready assembling of the parts and locking the same in place without the use of bolts, screws or similar fastening devices. A further object is to permit the use of long and short cartridges and the use of interchangeable barrels for firing cartridges of different caliber and at the same time provide compensating means to counteract the recoil when using cartridges of different length and power.

In order to accomplish the desired result, use is made of a recoil operated breech block, a compensating sleeve provided with shell exit openings, one located in front of the other and of different length for the discharge of empty shells of different length, and means which in one position lock the said compensating sleeve against movement, and in another position allow the compensating sleeve to move with the breech block. Use is also made of a barrel receiver arranged to hold barrels of differently sized bores, and a frame on which the barrel receiver is removably held and which has means engaging the barrel to lock the same in position on the receiver. Use is also made of means for quickly converting the hand firearm from an intermittent firing arrangement to an automatic one or vice versa.

A practical embodiment of the invention is represented in the accompanying drawings forming a part of this specification, in which similar characters of reference indicate corresponding parts in all the views.

Figure 1 is a side elevation of the hand firearm with the parts in position for firing long cartridges;

Fig. 2 is a plan view of the same;

Fig. 3 is a longitudinal central section of a portion of the firearm and with one side plate removed to show the trigger mechanism and adjacent parts in elevation;

Fig. 4 is a similar view of the same with

the recoil operated breech block shown in elevation and in rearmost recoil position;

Fig. 5 is an enlarged cross section of the same on the line 5—5 of Fig. 1;

Fig. 6 is a similar view of the same with the breech block cap removed and shown in dotted lines and the ejector in position to hold the firing pin from leaving the breech block;

Fig. 7 is a perspective view of the sear; 65

Fig. 8 is a similar view of the trigger;

Fig. 9 is a perspective view of the member for setting the hand firearm for intermittent or automatic firing;

Fig. 10 is a perspective view of the locking device for the magazine; 70

Fig. 11 is a perspective view of the locking lever for locking the breech block in recoil position after the last cartridge has been fired; 75

Fig. 12 is a perspective view of the main frame;

Fig. 13 is a perspective view of the breech block;

Fig. 14 is a perspective view of the extractor; 80

Fig. 15 is a perspective view of the firing pin;

Fig. 16 is a perspective view of the breech block cap and rear sight; 85

Fig. 17 is a front end view of the barrel holder;

Fig. 18 is a perspective view of the magazine with parts broken out;

Fig. 19 is a plan view of the same; 90

Fig. 20 is a transverse section of the upper end of the magazine, the section being on the line 20—20 of Fig. 19;

Fig. 21 is a sectional plan view of the same with the magazine locked in locking 95 position;

Figs. 22 and 23 are diagrammatic views showing cartridges of different caliber in the magazine;

Fig. 24 is a perspective view of the barrel 100 receiver;

Fig. 25 is a perspective view of the barrel;

Fig. 26 is a perspective view of the locking member for locking the sleeve to the breech block or to the barrel receiver; 105

Fig. 27 is a rear perspective view of a portion of the breech block sleeve, showing more particularly the seat for the reception of the pin of the sleeve locking plate;

Fig. 28 is a sectional plan view of the 110

same on the line 28—28 of Fig. 27 and with the sleeve locking plate in locking position;

Fig. 29 is a side elevation of a portion of the firearm with the parts in position for 5 automatic firing;

Fig. 30 is an inverted sectional plan view of the lower end of the magazine, the section being on the line 30—30 of Fig. 18; and

Fig. 31 is a cross section of the bottom 10 slide of the magazine.

The main frame 10 of the firearm is provided with a suitable handle 11 and a trigger guard 12. The forward end of the main frame 10 is provided with integral half-round pivots 13 adapted to be engaged by correspondingly shaped notches 14 formed in the sides 15 of a barrel receiver 16 to permit of swinging said barrel receiver 16 into and out of position on the main frame 10 15 when assembling or disassembling the firearm. The sides 15 fit snugly over the sides of the main frame 10 so as to hold the parts mounted on the said frame against accidental displacement. The barrel receiver 16 is provided with a central bore 17 into which fits the rear reduced end 18 of the barrel 19 provided with a shoulder 20 abutting against the forward end of the barrel receiver 16, as plainly indicated in the drawings. The bottom of the reduced portion 25 of the barrel receiver 16 is provided with a recess 21 engaged by a lug 22 forming an integral part of the main frame 10 and extending through an opening 23 formed in the bottom 30 of the barrel receiver 16 to lock the barrel 19 in position in the receiver and to lock the barrel receiver against longitudinal movement on the main frame 10. The rear end of the reduced end 18 of the barrel 19 is flush 35 with the rear end of the barrel receiver 16 and is provided at the bottom with a beveled lug 24 fitting into a notch 25 formed in the top of a lug 26 which is an integral part of the main frame 10, as plainly shown in Fig. 40 45 12. The back 27 of the lug 26 is beveled to correspond to the bevel of the lug 24 to guide the cartridge into the bore 28 of the barrel, as hereinafter more fully explained.

On the main frame 10 is mounted to slide forward and backward a breech block 30 provided with a forward extension in the form of two side bars 31, 32 (see Fig. 13) connected with each other at their forward 50 end by a crossbar 33. The lug 26 of the main frame 10, previously mentioned, fits between the sidebars 31, 32 to guide the breech block 30 in its forward and backward sliding movement. The under side of 55 the breech block 30 is provided with depending side flanges 34, 35 mounted to slide on guideways 36 formed on a lug 37 integral with the main frame 10 at the rear end thereof. The breech block 30 is held normally in a forward position by the action 60

of a spring 40 pressing with its forward end on the crossbar 33 of the breech block 30 and engaging with its rear end a recess 41 formed in the lug 26 of the main frame 10. In the crossbar 33 of the breech block 30 is 70 secured a forwardly extending rod 42 slidably engaging an open bearing 43 formed in the front end of the main frame 10. The outer end of the rod 42 is provided with a suitable head 44 adapted to be taken hold 75 of by the operator whenever it is desired to push the breech block rearwardly by hand for loading the firearm by hand and for other purposes, as hereinafter more fully explained. The rod 42 extends with its rear 80 end into the forward end of the spring 40 to hold the latter against accidental displacement.

The forward movement of the breech block 30 is limited by the forward end of the breech block 30 seating itself against the breech at the rear ends of the barrel 19 and the receiver to form a gas-tight joint. The cross-bar 33 at this time abuts against the back of the forward end 45 of the main frame 90 10. The breech block 30 is provided with a longitudinal bore 46 in which is mounted to slide a firing pin 50 having its reduced forward striking end 51 extending through the forward end of the breech block 30 to fire 95 the cartridge held in the bore 28 of the barrel 19. The firing pin 50 is provided near its rear end with a collar 52 against which presses the rear end of a firing pin spring 53 held in the bore 46 and abutting with its forward end against the forward end of the bore 46. Thus the firing pin 50 is normally held in rearmost position. The rear end 54 of the firing pin 50 extends through a cap 60 locked on the rear end of the breech block 105 30 by the said rear end of the firing pin 50. The cap 60 is in the form of a saddle (see Figs. 5, 6 and 16) provided at its sides with vertical guideways 61 engaging corresponding grooves 62 formed exteriorly on the sides 110 of the breech block 30, as plainly shown in Fig. 13. In order to place the cap 60 downward in position on the breech block 30 the firing pin 50 is pushed forward by a suitable tool to allow the cap 60 to drop down in 115 place, after which the firing pin 50 is released to allow its rear end 54 to pass through an opening 63 in the rear end of the cap, as plainly indicated in Fig. 3. Thus when the rear end 54 engages the opening 63 120 the cap 60 is held against upward movement on the breech block 30 and the cap 60 is held against longitudinal movement by its guideways 61 engaging the grooves in the breech block 30.

The rear projecting end of the firing pin 50 is adapted to be engaged by a hammer 70 fulcrumed on a pin 71 attached to the main frame 10.

On the heel 72 of the hammer 70 is pivot- 130

ed a link 73 extending downwardly into a bore 74 formed in the back of the handle 11, as plainly shown in Fig. 3. The lower end of the link 73 engages the concave upper face 75 of a plunger 76 mounted to slide in the bore 74. A spring 77 is held in the bore 74 and presses against the under side of the plunger 76 to force the latter upward to cause the link 73 to impart a forward 10 swinging motion to the hammer 70 whenever the latter is released, as hereinafter more fully explained.

By the arrangement described, the hammer 70 slowly follows the breech block 30 15 on the latter's forward motion caused by the straight line pressure of the spring 40, that is, the breech block 30 moves faster than the hammer 70 especially as the upper end of the link 73 bears against the heel of the hammer almost in alinement with the pivot 71 at the time the hammer 70 is in rearmost position. By this construction the pressure of the front upper portion or nose 20 of the hammer 70 against the under side of the breech block 30 is as light as possible at the time the hammer 70 and breech block 30 are in rearmost position (see Fig. 4) and the breech block 30 is free to close the breech 25 tightly when reaching a forward position 30 and completely clearing the hammer 70 thus insuring perfect locking of the firearm and allowing the hammer 70 to strike the rear end of the firing pin 50 with full force and thereby prevent misfiring.

35 The heel 72 of the hammer 70 is provided with a shoulder 78 adapted to be engaged by the tooth 81 of a sear 80 mounted to rock and to slide lengthwise in the frame 10. The sear 80 in construction and action is 40 practically the same as the one shown and described in the application for Letters Patent for a firearm, Serial No. 35,803, filed by me on June 23, 1915. The forward end of the sear 80 is pressed on by a spring 82 to 45 normally hold the sear 80 in rearmost position to engage the hammer 70 and to hold the same in cocked position. The spring 82 is mounted on a pin 83 provided with a head 84 having a transverse knife edge 85 bearing on the front wall of a slot 86 formed in the main frame 10. The knife edge 85 allows a free up and down rocking movement of the sear 80. The rear end of the sear 80 is provided with a rounded off pivot 87 extending loosely into a transverse bearing 88 formed in the main frame 10 to allow the sear to rock up and down and also to allow forward and rearward movement of the said sear. The sear 80 is provided near its forward end with a square shoulder 89 adapted to be engaged by a projection 91 formed on the trigger 90 provided with a pivot 92 (see Fig. 8) journaled in the right-hand side of the main frame 10. The trigger 90 is provided with a fingerpiece 93 extending into

the trigger guard 12 to be in convenient position for the operator's finger for pressing the trigger whenever it is desired to move the sear 80 forward against the tension of the spring 82 to release the hammer 70 for 70 firing purposes.

In order to impart a rocking motion to the sear 80 the following arrangement is made: On the top of the sear 80 in the front of the shoulder 89 is arranged a controlling piece 75 100 (see Fig. 7) of U-shape and having its arms 101 mounted to slide in recesses 102 formed in the sides of the main frame 10 (see Fig. 12). The upper rounded off ends of the said arms 101 are adapted to engage 80 notches 103 formed in the under side of the sidebars 31, 32 of the breech block 30 (see Figs. 3 and 13). When the breech block 30 moves rearward then the notches 103 pass out of engagement with the arms and the 85 bottoms of the side bars 31 and 32 now press the piece 100 downward and with it the sear 80 rocking on the bearing 88.

It is understood that the breech block 30 moves rearwardly on the recoil action of the 90 fired gun and in doing so the cap 60 of the breech block 30 imparts a rearward swinging movement to the hammer 70 whereby the hammer is cocked and held in this position by the sear 80, while the breech block 95 immediately returns to its forward position by the action of its spring 40. When the operator presses the fingerpiece 93 then the sear 80 releases the hammer which swings forward by the action of its spring 77 to 100 cause the firing pin 50 to fire the cartridge in the barrel 19. The sear 80 is forced downward by the spring 82 as soon as the pressure on the rear end of the sear 80 is relieved by the release of the hammer 70. 105

When it is desired to automatically fire the gun use is made of a disk-shaped catch 110 specially designed to keep the sear 80 in raised position (see Fig. 29), that is, in alinement with the lug 91 of the trigger 90 110 so that when the latter is pressed the lug 91 bears constantly on the square shoulder 89 of the sear 80. When the catch 110 is not in active position (see Figs. 3 and 4) then the square shoulder 89 is below the lug or projection 91. The catch 110 is provided with a transversely extending pivot 111 (see Fig. 9) fitting into a bearing 112 formed on the trigger 90 in axial alinement with its pivot 92. The catch 110 is provided with a forwardly extending lug 113 having a beveled face 114 adapted to engage a beveled face 115 formed on one side of the sear 80 adjacent to the square shoulder 89 (see Fig. 7). The end of the lug 113 is provided with a short projection 116 adapted to engage the under side of the sear 80 under the beveled face 115. It will be noticed that when the catch 110 is in the position shown in Fig. 29 with the fingerpiece 93 of the trigger 90 120 125 130

pressed then the sear 80 is held locked in forward position with the tooth 81 out of the path of the hammer shoulder 78 to prevent the hammer from being cocked on 5 swinging rearwardly by the rearwardly moving breech block 30. Thus the hammer immediately returns to forward position and strikes the firing pin 50 to fire a shot. This operation is repeated as long as the fingerpiece 93 is held pressed by the operator as the sear 80 cannot engage and hold the hammer 70 in cocked position as long as the sear is in this forward position, but as soon as the fingerpiece 93 is released the 10 sear can return to normal position to hold the hammer 70 in cocked position when swung rearwardly by the next action of the breech block 30. When the firearm is not used for automatic firing the catch 110 is held in the position shown in Fig. 3, that is, with the lug 113 out of engagement with the sear 80. The bottom of the catch 110 is provided with a fingerpiece 117 extending into the trigger guard 12 to permit the 15 operator to turn the catch 110 into inactive or active position, as the case may be. The catch 110 is pressed on by a spring 118 interposed between the catch 110 and a locking and releasing bolt 120 for the magazine 121. When the catch 110 is turned into active position then the beveled face 114 of the catch 110 bears against the face 115 of the sear 80 and owing to the action of the spring 118 the sear is pushed upward at 20 the time the hammer 70 is out of engagement with the sear 80, the spring 118 overcoming the tendency of the spring 82 to force the sear 80 downward. It is understood that when the hammer 70 engages the sear 80 the forward end thereof remains upward as the spring 77 is more powerful than the spring 82. The face 114 of the catch 110 prevents the forward end of the sear 80 from being forced down and hence 25 as long as the catch 110 is in active position the square shoulder 89 of the sear 80 remains engaged with the lug 91 of the trigger 90. The result is that whenever the catch 110 is turned into active position the lug 30 91 of the trigger 90 bears against the shoulder 89 of the sear 80 notwithstanding the fact that there may be no force on the tooth 81 of the sear 80 to cause the forward end to remain raised such as happens when the 35 hammer 70 is down. Thus when the catch 110 is in active position the hammer 70 is free to function as long as the trigger 90 is kept pressed and hence the firearm is automatic in its action. The magazine 121 is 40 slidable in the handle 11 and is adapted to hold cartridges 122 of small caliber in staggered relation, as indicated in Fig. 22, or the magazine is adapted to hold cartridges 123 of larger caliber, one directly above 45 the other, as indicated in Fig. 23. The car- tridges 122 and 123 are forced upward in the magazine 121 by a follower 124 pressed on by a spring 125 resting with its lower end on a removable bottom slide 126 mounted to slide on the lower end of the magazine 70 121. The slide 126 is provided with a fingerpiece 127 and is flush with the bottom of the handle 11. The magazine 121 is provided at its sides near the back with inwardly projecting guide ribs 128 (see Fig. 75 21) for engagement with the forward faces of the rims of the cartridges to prevent short cartridges from sliding forward in the magazine and to properly guide the cartridges in their upward movement. The 80 ribs 128 also serve to hold the cartridges in staggered relation to each other, as shown in Fig. 22. Similarly inwardly extending guide ribs 129 are formed on the sides of the magazine in front of the ribs 128 and 85 parallel therewith to keep the noses of the cartridges in a vertical line and to guide the forward ends of the cartridges in their upward movement. It will be noticed that by the use of the ribs 128 and 129 the 90 cartridges are kept parallel and are moved upward by the follower 124 approximately parallel with the line of movement of the breech block 30. The upper ends of the rear portions of the sides are bent inwardly 95 to form retaining lips 130 to guide the uppermost cartridge when pushed forward by the returning breech block 30, as hereinafter more fully explained. The upper forward portions of the sides of the 100 magazine 121 are provided with resilient centering lips 131 extending inwardly, as plainly shown in Fig. 19, to hold the uppermost cartridge properly centered relatively to the bore 28 of the barrel 19 at the 105 time of pushing this uppermost cartridge into the said barrel bore. The lips 131 are held on the upper ends of spring tongues 132, struck up from the sides of the magazine 121, and the lips 131 are of sufficient 110 length to hold both long and short cartridges. The front of the magazine 121 is provided with an opening 133 adapted to be engaged by the rear end 134 of the locking and releasing bolt 120, previously 115 mentioned, and mounted to slide forward and backward in a suitable guideway 135 formed in the left-hand side of the main frame 10. The bolt 120 is provided with a suitable fingerpiece 136 extending through 120 a bayonet slot 136^a formed in the left-hand side 15 of the barrel receiver 16 to be within convenient reach of the operator to enable the latter to unlock the magazine for removal from the handle 11 for 125 refilling or other purposes. It is understood that the spring 118 pushes the bolt 120 rearwardly to hold the lug 134 normally in engagement with the opening 133 thus locking the magazine 121 in posi- 130

tion in the handle 11. When it is desired to remove the magazine 121 the operator pushes the finger piece 136 forward to disengage the lug 134 from the opening 133 thus unlocking the magazine 121 and allowing the same to be removed in a downward direction from the handle 11.

When using large caliber rimless cartridges 123 the magazine 121 is made with straight sides, that is, the ribs 128 and 129 are omitted to accommodate large caliber cartridges without rims in a magazine fitting into the handle 11.

The follower 124 is provided on both sides with raised fingerpieces 138, extending into slots 139, formed in the sides of the magazine 121. By the arrangement described the user can readily take hold of the fingerpieces 138 with the thumb and forefinger of one hand and push the follower 124 downward against the tension of the spring 125 to allow of readily filling the magazine with cartridges by way of the top of the magazine.

When using cartridges of different calibers, barrels 19 with corresponding bores have to be used, and as such barrels can be interchanged in the barrel receiver, it is evident that the firearm can be used for firing larger and smaller caliber cartridges. In case larger caliber cartridges of the rimless variety are used a correspondingly heavier compensating sleeve 140 is employed and the firing pin 50 is arranged for center firing.

It is also permissible to use longer and shorter cartridges, and for this purpose the following arrangement is made: A saddle-shaped sleeve 140 is mounted to slide on the top of the barrel receiver 16 and on the breech block 30, and use is made of a thin spring locking plate 141 for locking the said sleeve 140 either to the breech block 30 so as to move with the latter, or to lock it to the barrel receiver sides 15 to hold the sleeve 140 against movement and to allow the breech block 30 to slide forward and backward within the said sleeve 140. The sleeve 140 forms, with the rear end of the barrel receiver 16, the barrel, the top of the main frame 10 and the breech block 30, the breech block chamber 142 into which projects the upper end of the magazine 121, as plainly indicated in Figs. 3 and 4. The right-hand side of the sleeve 140 is provided with two elongated exit opening 143 and 144 (see Fig. 2) arranged one in front of the other and of which the front exit opening 143 is for the discharge of long empty shells while the exit opening 144 is for the discharge of short empty shells. It is understood that when the sleeve 140 is locked by the locking plate 141 to the sides 15 of the barrel receiver 16 then the front opening 143 is closed by the receiver 16, and the rear opening 144 is uncovered by the breech block 30 when the latter moves into rearmost position and conse-

quently short empty shells are discharged through the said exit opening 144. When the sleeve 140 is locked by the locking plate 141 to the cap 60 of the breech block 30 then it moves with the breech block rearwardly and in doing so the forward exit opening 143 is moved rearwardly beyond the rear end of the barrel receiver 16 and in register with the chamber 142 (see Fig. 4) to allow long empty shells to be discharged through the said exit opening 143. The locking plate 141 is provided at its front end with a pivot 145 provided with a lengthwise elongated head 146 adapted to pass through a correspondingly shaped diagonal opening 147 formed in the left-hand side of the sleeve 140 to engage the head 146 with a seat 148 formed in the inner face of the said left-hand side of the sleeve 140 (see Figs. 26 and 27). After the head 146 has passed through the opening 147 in upwardly and rearwardly inclined position relatively to the sleeve 140 (see dotted lines in Fig. 1) the plate can be swung downward into the position shown in full lines in Fig. 1. The rear end of the plate 141 is provided with a locking pin 150 adapted to engage either of two openings 151 and 152, of which the opening 151 is formed in the left-hand side 61 of the cap 60 (see Fig. 16), and the opening 152 is formed in the left side 15 of the barrel receiver 16. It is understood that the plate 141 after being engaged by its head 146 with the seat 148 can be sprung outward and then swung downward to engage the pin 150 with either of the said openings 151 or 152, the plate being held flat against the outer face of the sleeve 140 and the left side 15 with the pin 150 extending in either opening 151 or 152. It will be noticed that the locking plate 141 holds the several parts in assembled position and no further screws, bolts, or similar fastening device are needed for fastening the several parts of the firearm in position on the main frame 10. When it is desired to disassemble the firearm, it is necessary for the operator to disengage the pin 150 from either opening 151 or 152, then swing the plate 141 upward into the position shown in dotted lines in Fig. 1 to allow of disengaging the head 146 from the seat 148 for the removal of the plate. When this has been done the remaining parts of the firearm can be readily taken apart, one by one.

In order to guide the sleeve 140 on the barrel receiver 16 and the breech block 30 use is made of longitudinally extending ribs 153 formed on the inner faces of the sides of the sleeve 140 and engaging longitudinal grooves 154 formed in the sides of the barrel receiver 16 and similar grooves 155 formed in the sides of the breech block 30 and extending from end to end thereof to allow of sliding the sleeve 140 off the breech

block 30 when disassembling the parts and after the cap has been removed. The sides of the sleeve 140 are flush with the sides of the cap 60 and the rear end of the sleeve 140 5 abuts against the front face of the cap 60 at the time the sleeve is locked to the cap by the locking plate 141, as previously explained. The sleeve 140 when coupled to the breech block 30 acts as a compensating 10 device for the same at the time when cartridges of different length, higher power or caliber are used. It is understood that by the use of this compensating sleeve 140 weight is added to the breech block 30 thus 15 increasing the inertia thereof when cartridges of greater power are used to compensate for the more forceful recoil action of the breech block 30.

The shell extractor 160 is removably held 20 and adapted to turn in a bore 161 formed in the right-hand side of the breech block 30, as shown in Fig. 13. The extractor 160 consists of a shank 162 terminating in flattened spring portions 163 and 164 standing 25 at a right angle one to the other, and of which the forward end of the spring portion 164 terminates in a hook 165 adapted to engage the rim of the exploded shell to withdraw the same from the bore 28 of the barrel whenever the breech block 30 moves rearwardly. The hook 165 is adapted to engage 30 a short incline 166 on the right-hand side of the rear end of the barrel 19 to readily engage the front face of the rim of the shell, 35 at the time the breech block 30 moves into forward position. The hook 165 is somewhat broader than the forward end of the flattened spring portion 164 so that the projecting lower end of the hook 165 is adapted 40 to abut against the front face of the breech block 30 to prevent rearward movement of the extractor 160 in the bore 161. The rear end of the shank 162 is provided with an angular arm 167 adapted to engage the rear 45 end of the firing pin 50 to hold the latter in forward position in the breech block 30 whenever it is desired to remove the cap 60. The extractor 160 is adapted to be turned by the cap 60 and for this purpose the rear 50 end of the extractor is provided with an upwardly extending lug 168 and a cam face 169 at the base of the lug (see Figs. 5, 6 and 14). The lug 168 is adapted to be seated in a recess 170 formed in the rear end of 55 the breech block 30 and when the lug is in this position the arm 167 extends over the rear end of the firing pin 50, as plainly shown in Fig. 6. When the cap 60 is placed in position on the breech block 30 it is held 60 in a slightly inclined position (see dotted lines in Fig. 6) so that the lower edge of the right-hand side of the cap 60 engages the cam surface 169 and imparts a slight turning motion to the extractor 160 so that 65 the pin 168 extends in a vertical groove 171

formed in the inside of the right-hand side of the cap 60. The groove 171 terminates in an outwardly and upwardly extending opening 172 into which the lug 168 passes at the time the cap 60 moves into lowermost 70 position whereby a further turning motion is given to the extractor 160 to move the arm 167 out of engagement with the rear end of the firing pin 50 to permit the spring 53 thereof to push the firing pin rearwardly. 75 so that the rear terminal 54 passes through the opening 63 in the cap 60 for engagement by the hammer 70, as previously mentioned. It will be noticed that when the lug 168 fully engages the opening 172 then the extractor 160 has been turned so that its hook 165 stands in a vertical position and is held in this vertical position by the lug 168 engaging the opening 172.

On the forward end of the lug 37 of the 85 main frame 10 is formed an integral ejector 180 (see Fig. 12) located to one side of the longitudinal axis of the barrel to engage the left-hand side of the empty shell rim at the time the latter is drawn rearwardly by 90 the hook 165 of the extractor 160. By this arrangement a sidewise swinging movement is given to the empty shell to eject the same through the exit opening 143 or 144, as the case may be. A groove 181 is formed in the 95 under side of the breech block 30 for the passage of the ejector 180, as indicated in Figs. 5 and 6.

In order to indicate to the user that the last cartridge has been fired, the following 100 arrangement is made: A lever 190 (see Figs. 3, 4, and 11) is fulcrumed at 191 on the left-hand side of the main frame 10, and this lever has its forward end in the form of a fingerpiece 192 extending into the 105 trigger guard 12 at the top thereof and in front of the fingerpiece 93 of the trigger 90. The rear end of the lever 190 is provided with a transversely extending lug 193 extending into a recess 194 formed in the 110 front end of the magazine 121 at the upper end thereof, as plainly shown in Figs. 3 and 18. The lug 193 projects into the path of the follower 124 and the rear end of the lever 190 is provided with an upwardly 115 extending locking lug 195 adapted to engage a notch 196 formed in the bottom of the side bar 31 of the breech block 30 to lock the latter in rearmost recoil position after the last cartridge has been fired. The 120 lever 190 is normally held in inactive position by the use of a spring 197 interposed between the lever 190 and a lug 198 formed on the trigger 90 (see Figs. 3, 4 and 8.) The spring 197 assists the spring 118 in 125 holding the trigger 90 normally in forward position, and in case one of the said springs should break the other causes the trigger to function properly. It is understood that as long as the follower 124 is in lowermost 130

position and gradually feeds up the cartridges, the lever 190 does not act on the breech block but when the follower 124 moves into uppermost position it engages the lug 193 and imparts a swinging motion to the lever 190 so that on the next rearward movement of the breech block 30 after the last cartridge is fired the locking lug 195 snaps into the notch 196 and thus locks the breech block in rearmost recoil position. The user of the firearm is thus made aware that the last cartridge has been fired and the magazine is empty. In order to continue continuous firing the empty magazine 121 is replaced by a filled one and then the fingerpiece 192 is pressed upward to impart a return swinging motion to the lever 190 with a view to disengage the lug 195 from the notch 196, thus permitting the breech block 30 to move forward.

The barrel 19 is provided at the top near the front end with a front sight 200 and a rear sight 201 is arranged on the top of the cap 60, and this rear sight 201 is provided with a longitudinally extending aperture 202 in alinement with the sight 200. Directly above this aperture 202 is formed a longitudinally extending notch 203 having its bottom in close proximity to the top of the aperture 202 to eliminate the usual blurring caused by open sights. By the arrangement described very fine and accurate sighting is had.

In order to form a bearing for the slide 126 on the lower end of the magazine 121, use is made of ledges 210 on the sides of the slide and engaging guideways 211 formed by cutting slots in the ribs 128 and 129 in the sides of the magazine. The lower forward portion of the magazine is provided with struck-up spring locking lips 215 extending toward each other and engaging the raised portion of the slide 126 to normally hold the slide locked in closed position. The locking lips 215 readily yield on the operator exerting an outward pull on the fingerpiece 127 of the slide 126 to allow of removing the same from the lower end of the magazine.

The operation is as follows:

When the several parts are in the position shown in Figs. 1, 2 and 3, with the magazine 121 filled with cartridges and one being in the breech of the barrel, then the operator first moves the hammer 70 into cocked position and then presses the trigger 90 to move the sear 80 forward and thereby release the hammer 70 which, by the spring mechanism is caused to swing forward and strike the firing pin 50 to fire the cartridge. When this takes place the breech block 30 recoils and in doing so swings the hammer 70 back into cocked position. The empty shell moves rearward out of the barrel by the recoil of the exploded shell aided by the

extractor 160, and the left-hand side of the cartridge rim finally abuts against the ejector 180 so that the empty shell is deflected to the right owing to the action of the extractor and passes through the corresponding exit opening 143 or 144 to the outside. The uppermost cartridge in the magazine 121 is engaged by the lug 38 at the front end of the breech block 30 whereby the uppermost cartridge is pushed forwardly and into the bore 28 of the barrel 19, it being understood that the breech block is returned to its normal foremost position by the action of its spring 40. On pressing the trigger 90 a second time the cocked hammer 70 is released and a second shot is fired, and then the above described operation is repeated except that it is not necessary for the operator to cock the hammer 90 as this is done by the breech block 30. When the last cartridge in the magazine 121 has been fired then the follower 124 presses on the lug 193 of the lever 190 so that the breech block 30 is locked in rearmost position by the lug 195 of the lever 190 and when it is desired to return the breech block to forward position the operator presses the fingerpiece 192 in an upward direction to disengage the locking lug 195 from the notch 196 and thus release the breech block 30.

When it is desired to fire automatically, it is necessary to change the position of the catch 110, as previously explained, so that the sear 80 is held in forward position thus preventing the tooth 81 from engaging the shoulder 78 of the hammer 70, and consequently the hammer swings forward and eventually strikes the firing pin 50 as previously explained. The above described operation is repeated as long as the fingerpiece 105 93 of the trigger 90 is held pressed and cartridges are in the magazine 121. When the last cartridge has been fired the breech block is arrested by the action of the lever 190, as before explained.

When it is desired to load by hand, it is only necessary for the operator to push the rod 42 and consequently the breech block 30 rearwardly to uncover the corresponding exit opening 143 or 144 to allow of passing a long or a short cartridge through this opening into the breech block chamber 142 so that on the release of the push rod 42 the breech block 30 returns and pushes the cartridge into position in the breech of the barrel 19.

In order to securely lock the barrel receiver 16 in position on the frame 10 and to prevent movement in a lengthwise direction, the rear edges 220 of the side plates 15 are beveled in a rearward and upward direction (see Figs. 1 and 24) and the said edges 220 are seated on correspondingly shaped shoulders 221 formed on the frame 10.

The lug 45 on the frame 10 is provided

130

on top with a rabbet 222 into which fits a depending shoulder 223 formed on the under side of the barrel receiver 16 so that in case it is desired to take the firearm apart, 5 the operator first removes the magazine 121 and the locking plate 141 and then engages the pin 150 with the rear end 54 of the firing pin 50 and presses the latter forward so that the rear end 54 moves out of the aperture 10 63 and then the pin 150 moves into the said aperture 63. The operator now exerts an upward pull on the plate 141 and thereby lifts the cap 60 out of position on the rear end of the breech block 30. In lifting the 15 cap 60, lug 168 of the extractor 160 moves out of the angular aperture 172 whereby the extractor 160 is turned and the arm 167 engages the rear end of the firing pin 50 and holds the same locked in forward position 20 against the tension of the spring 53 to permit of conveniently replacing the cap 60 on reassembling the parts. The sleeve 140 can now be moved rearwardly and out of engagement with the barrel receiver 16 and 25 the breech block 30. The barrel receiver 16 is next unlocked by pushing the finger-piece 136 to the left and the barrel receiver can now be swung upward on the pivots 13 to release the barrel receiver from the 30 lug 22 and to disengage the left side 15 from the fingerpiece 136 of the magazine lock 120 after which a slight rearward pull on the barrel receiver 16 disengages the same from the pivots 13 and it can then be lifted off 35 the frame 10. The barrel 19 now becomes unlocked and can be removed from the barrel receiver 16 and the breech block 30 can be lifted off the frame 10. Ready access is now had to the trigger mechanism, the sear, 40 the catch 110 and the various other parts for removal or inspection of the same, if desired. The parts can be readily assembled in reverse order, it being understood that in replacing the cap 60 a turning motion is 45 given to the extractor 160 so that its arm 167 unlocks the firing pin 50 and the latter now moves into rearmost position by the action of its spring 53 and in doing so the end 54 passes into the opening 63 and thereby locks the cap 60 in place.

When it is desired to remove the follower 124 and the spring 125 from the magazine 121, the operator pulls out the bottom slide 126 to permit of removing the spring and the follower by way of the lower end of the magazine.

In order to enable the user to readily change the position of the catch 110 for automatic firing, it is necessary for the user 60 to first cock the hammer 70 and slightly press the trigger finger 93 to push the sear 80 sufficiently far forward to allow of turning the catch 110 from the position shown in Figs. 3 and 4 to that shown in Fig. 29.

65 In order to turn the catch 110, the operator

takes hold of the fingerpiece 117 with a finger nail or a tool and presses the same downward and rearward to turn the catch. For changing the firearm from automatic to intermittent firing the catch 110 is returned 70 to the original inactive position.

Having thus described my invention, I claim as new and desire to secure by Letters Patent:

1. In a hand firearm, the combination of 75 a recoil operated breech block and a compensating sleeve adapted to move bodily with the breech block to compensate for an increase in the force of the recoil action of the breech block.

2. In a hand firearm, the combination of 80 a recoil operated breech block, and a compensating sleeve moving bodily with the breech block to increase the inertia thereof on an increase in the force of the recoil action of the breech block.

3. In a hand firearm, the combination of 85 a recoil operated breech block and a compensating member comprising a movable sleeve to increase the inertia of the breech block 90 on an increase in the force of the recoil action of the breech block, and locking means for locking the said compensating member to the breech block or unlocking it therefrom and holding it against movement.

4. In a hand firearm, the combination of 95 a recoil operated breech block, a compensating sleeve mounted to slide thereon, and means connecting the said sleeve with the said breech block to cause the sleeve to move 100 with the breech block, the said means being adapted to be disengaged from the breech block and to be engaged with a fixed part of the firearm to lock the sleeve against movement.

5. In a hand firearm, the combination of 105 a recoil operated breech block provided with shell extracting and ejecting means, and exit means coacting with the said breech block and the said extracting and ejecting means and having shell exit openings one in front of the other to discharge empty shells of different lengths.

6. In a hand firearm, the combination of 110 a recoil operated breech block, ejecting means for ejecting an empty shell, a member operating in conjunction with the said ejecting means and having shell exit openings one in front of the other for the discharge of shells of different lengths, and means which 115 in one position hold the said member against movement and in another position cause the member to move with the breech block.

7. In a hand firearm, the combination of 120 a recoil operated breech block, a shell discharge and compensating sleeve provided with shell exit openings one located in front of the other for the discharge of shells of different lengths, and locking means which 125 in one position lock the said sleeve against 13

movement and in another position lock the sleeve to the said breech block to move with the same.

8. In a hand firearm, the combination of a recoil operated breech block, a main frame, a barrel receiver mounted on the said frame, a barrel removably attached to the said barrel receiver, a compensating sleeve mounted to slide on the said barrel receiver and slidably engaged by the said breech block, the said sleeve being provided in one side with exit openings of different lengths and located one in front of the other, ejecting means operating in conjunction with the said sleeve and its openings to discharge a shell through either opening, and means which in one position lock the said sleeve to the said barrel receiver and in another position lock the sleeve to the said breech block.

20 9. In a hand firearm, the combination of a recoil operated breech block, a main frame, a barrel receiver mounted on the said frame, a barrel removably attached to the said barrel receiver, a compensating sleeve mounted to slide on the said barrel receiver and slidably engaged by the said breech block, the said sleeve being provided in one side with exit openings of different lengths and located one in front of the other, ejecting means operating in conjunction with the said sleeve and its openings to discharge a shell through either exit opening, and a locking plate provided with pins at its ends, the said sleeve having a pin seat for the reception of one 30 of the plate pins to allow of imparting a swinging movement to the plate, and the said breech block and the said barrel receiver having holes adapted to be engaged by the pin of the plate to lock the sleeve to either the breech block or to the barrel receiver.

40 10. In a hand firearm, the combination of a recoil operated breech block, a main frame, a barrel receiver mounted on the said frame, a barrel removably attached to the said barrel receiver, a compensating sleeve mounted to slide on the said barrel receiver and slidably engaged by the said breech block, the said sleeve being provided in one side with exit openings of different lengths and located one in front of the other, ejecting means operating in conjunction with the said sleeve and its openings to discharge a shell through either exit opening, and a locking plate provided at one end with a pivot pin having an elongated head and provided at the other end with a locking pin, the said sleeve having a pivot pin seat adapted to be engaged by the said pivot pin to allow of imparting a swinging movement to the plate, the said breech block and the said barrel receiver having openings adapted to be engaged by the locking pin of the plate to lock the sleeve to the breech block or to the barrel receiver.

55 11. In a hand firearm, the combination of

a barrel receiver, a barrel removably mounted on the said barrel receiver and having a reduced rear portion provided at the bottom with a recess, a main frame provided with a locking lug and engaging the said recess 70 on the barrel to lock the latter in place in the bore of barrel receiver.

12. In a hand firearm, the combination of a barrel having a reduced rear portion provided at the bottom with a recess, a main 75 frame provided at the top with a locking lug, the front end of the frame being provided with a transverse pivot, and a barrel receiver having a bore for the reception of the said reduced end of the barrel, the bottom of the bore having an opening for the passage of the said locking lug to engage the said barrel recess, the said barrel receiver having depending side plates fitting the sides of the frame, the front edges of the said 80 side plates having bearings engaged by the said pivot.

13. In a hand firearm, the combination of a barrel having a reduced rear portion provided at the bottom with a recess, the rear 90 end of the barrel being provided at the bottom with a retaining lug, a main frame provided at the top with a locking lug, the front end of the frame being provided with a transverse pivot, the said frame being provided in the rear of the said locking lug with a bearing engaged by the said retaining lug of the barrel, to hold the latter against turning, and a barrel receiver having a bore for the reception of the said reduced end of the barrel, the bottom of the bore having an opening for the passage of the said locking lug to engage the said barrel recess, the said barrel receiver having depending side plates fitting the sides of the 95 frame, the front edges of the said side plates having bearings engaged by the said pivot.

100 14. In a hand firearm, the combination of a main frame, a barrel receiver mounted to swing on the said main frame, a barrel removably mounted on the said barrel receiver, means for locking the said barrel and the receiver to the said frame, and interlocking retaining means on the rear end of the barrel 110 and on the frame for holding the said barrel 115 against turning.

15. In a hand firearm, the combination of a main frame having a beveled guide and retaining member, the top of which is provided with a bearing, and a barrel provided 120 at the bottom of its rear end with a rearwardly extending lug fitting into the said bearing, the rear end of the said lug being beveled and flush with the beveled face of the said guide and retaining member to 125 guide a cartridge into the bore of the barrel.

16. In a hand firearm, the combination of a breech block, a cap removably held on the rear end of the said breech block, a spring-pressed firing pin slidable in the said breech 130

- block, and an extractor mounted to turn in the said breech block and having a flange adapted to engage the said firing pin to hold the said firing pin against rearward movement at the time the cap is removed.
17. In a hand firearm, the combination of a breech block, a cap removably held on the rear end of the said breech block, a spring-pressed firing pin slidable in the said breech block, and an extractor mounted to turn in the said breech block and having a flange adapted to engage the said firing pin to hold the said firing pin against rearward movement, the said extractor having an angular lug adapted to be engaged by the said cap to turn the extractor into locking position relatively to the firing pin at the time the cap is removed.
18. In a hand firearm, the combination of a breech block, a spring-pressed firing pin slidable in the said breech block, and a cap removably held on the said breech block and engaged by the said firing pin to hold the cap against removal.
19. In a hand firearm, the combination of a breech block, a spring-pressed firing pin slidably mounted in the said breech block, a cap vertically removable on the rear end of the said breech block and through which projects the rear end of the firing pin to lock the cap to the breech block, the said firing pin being limited in its rearward movement by the said cap.
20. In a hand firearm, the combination of a breech block provided with a central bore and a second bore at one side, a spring-pressed firing pin slidably mounted in the said central breech block bore, and an extractor mounted to turn in the said second bore and provided at its forward end with a hook and at its rear end with a transverse flange adapted to engage the said firing pin and hold the latter against rearward movement.
21. In a hand firearm, the combination of a breech block provided with a central bore and a second bore at one side, a spring-pressed firing pin slidably mounted in the said central breech block bore, an extractor mounted to turn in the said second bore and provided at its forward end with a hook and at its rear end with a transverse flange adapted to engage the said firing pin to hold the latter against rearward movement, the said extractor being provided at its rear end with an upwardly extending lug, and a vertically removable cap held on the rear end of the said breech block and through which projects the rear end of the firing pin, the said cap having means engaging the said lug to turn the latter on placing the cap in position to disengage the flange from the shoulder.
22. In a hand firearm, the combination of a recoil operated breech block, a hammer controlled by the breech block, a sear mounted to rock up and down and to slide forward and backward to engage and disengage the hammer, a trigger controlling the said sear, and a catch adapted to engage the said sear to hold the latter in position for automatic firing as long as the trigger is held pressed.
23. In a hand firearm, the combination of a recoil operated breech block, a hammer controlled by the breech block, a spring-pressed sear adapted to engage the said hammer to hold the latter in cocked position, the said sear having an inclined shoulder, a trigger controlling the said sear, and a catch mounted to turn and having an incline engaging the said inclined shoulder on the sear to hold the latter upward and forward as long as the trigger is held pressed.
24. In a hand firearm, the combination of a sear mounted to rock up and down and to move forward and backward, the sear having a square shoulder and an inclined shoulder, a trigger adapted to engage the said square shoulder to move the sear forward into hammer release position, and a catch mounted to turn loosely on the trigger and having an inclined shoulder engaging the said inclined shoulder of the sear.
25. In a hand firearm, the combination of a sear mounted to rock up and down and to move forward and backward, the sear having a square shoulder and an inclined shoulder, a trigger adapted to engage the said square shoulder to move the sear forward into hammer release position, and a catch mounted to turn loosely on the trigger and having an inclined shoulder engaging the said inclined shoulder of the sear, the said catch having a forwardly extending lug engaging the under side of the sear at the inclined shoulder thereof.
26. In a hand firearm, the combination of a sear mounted to rock up and down and to move forward and backward, the sear having a square shoulder and an inclined shoulder, a trigger adapted to engage the said square shoulder to move the sear forward into hammer release position, and a spring-pressed catch mounted to turn loosely on the trigger and having an inclined shoulder engaging the said inclined shoulder of the sear.
27. In a hand firearm, the combination of a recoil operated breech block, a magazine having a follower, and a normally inactive locking lever for the breech block, the locking lever having a fingerpiece at one end and being adapted to engage with its other end the said breech block to lock the latter in recoil position, the said other end of the locking lever having a transverse lug extending into the path of the said follower for the latter to move the locking lever into locking position relatively to the breech block after the last cartridge has been fired.
28. In a hand firearm, a frame having

half round pivots at its front end, beveled shoulders near its rear end opposite the said pivots, and a barrel receiver detachably mounted to swing on the said pivots and having its rear edge beveled and seated on the said shoulders. 5

29. In a hand firearm, a frame having pivots at its front end, beveled shoulders near its rear end opposite the said pivots,

and a barrel receiver mounted to swing on 10 the said pivots and having its rear edge beveled and seated on the said shoulders, the front end of the frame having a rabbeted lug above the pivots and the barrel receiver having a depending flange engaging the said 15 rabbet.

WALDO E. ROSEBUSH.
